UNITED STATES PATENT OFFICE

2,511,785

PICTURE FRAME

Joseph A. Packheiser, Chicago, Ill.

Application November 23, 1946, Serial No. 712,023

1 Claim. (Cl. 40—152)

1

My invention relates to certain new and useful improvements in picture frames. More particularly, the invention relates to a simple and effective arrangement for releasably latching a picture assembly within the frame. As such, the invention has for one of its objects the provision of an improved construction of this character which will be highly efficient in use and economical in manufacture.

Among the several objects of this invention is the provision in a picture frame of an arrangement for latching a picture assembly within the frame by means which requires the use of no tools, nails or other like instruments and materials.

Another and equally important object of the invention is the provision for latching a picture assembly in a frame by means which can be readily removed by the insertion of the finger through a finger notch provided for that purpose.

A still further object of the invention is the provision of a latching arrangement for a picture assembly which requires no tools for mounting or removing the latching means from picture assembly latching position.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a picture frame embodying the invention;

Fig. 2 is a bottom plan view of the base shown in Fig. 1;

Fig. 3 is a sectional detail view taken substantially on line 3—3 of Fig. 1; and

Fig. 4 is a sectional detail view taken substantially on line 4—4 of Fig. 2.

The several objects of my invention are accomplished by the preferred form of construction shown and illustrated in the accompanying drawings. The form or design of the picture frame, so far as is material to the present invention, may vary according to the desire and taste of the manufacturer.

In the drawings, my improved picture frame comprises a base 10, which is substantially a flat elongated formation and serves to support the picture frame in an upright position.

Formed in this base, adjacent opposite ends thereof, are openings 11 and fixedly secured in these openings by friction or other means are the lower end portions of side frame elements 12.

These side frame elements 12 are provided with confronting grooves 13, into which the edge portion 14 of a picture assembly 15 are slidably received.

5 This picture assembly may consist of a glass 16, a picture 17 and a back plate 18.

The upper end portions of these side frame elements 12 are connected together by a top frame element 19, also having a groove (not shown), similar to the groove 13, for receiving the top edge portion of the picture assembly 15.

10 Formed in the base 10 is an elongated slot 20 communicating with the grooves 13 and through which the picture assembly 15 is passed for mounting in the grooves 13.

15 Formed in the base portion of the side frame elements 12, that is, the portions of these elements which may be referred to as a part of the base 10, are confronting notches 21. Mounted in the slot 20 is an elongated leaf spring acting as a latch bar of a width substantially less than the width of the slot 20, but of a sufficient width to have disposed thereon the lower edge portions 23 of the picture assembly 15. The opposite end 20 portions of this latch bar 22 project into the keeper notches 21. This latch bar 22, being formed of spring material, is capable of being flexed so as to disengage its opposite end portions from the notches 21.

25 30 To facilitate flexing this latch bar 22, I provide in the base 10, adjacent the slot 20, a finger notch whereby the finger may be projected to dispose either the nail or a portion thereof into flexing position with respect to the latch bar 22.

35 35 From the foregoing description taken in connection with the accompanying drawings, it is apparent that I provide a picture frame which is simple in structure, easy of assembly and thereby capable of being manufactured at an economical cost.

40 45 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

50 55 Having thus described my invention, what I claim as new and desire to protect by Letters Patent is:

A picture frame comprising a base, a top frame element, side frame elements extending upwardly from the base and connecting the base to the top

frame element and having confronting grooves formed therein, said base having an elongated slot formed therein in communication with the grooves, said side frame elements adjacent the ends of the slot having notches formed therein, and an elongated flexible member removably mounted in the slot with its opposite end portion extending into said notches to provide a support for a picture assembly arranged between the side frame elements and the base and the top frame elements with corresponding side portions confined in said grooves, said flexible member being adapted to be flexed laterally of its longitudinal length to disengage its opposite end portions from said notches to permit removal of said picture.

assembly through said slot from between said side frame elements.

JOSEPH A. PACKHEISER.
